Attorney

UNITED STATES PATENT OFFICE.

STEPHEN LOUIS GARTLAN, OF TORONTO, ONTARIO, CANADA, ASSIGNOR OF FIFTY-FIVE ONE-HUNDREDTHS TO ALBERT EDWARD GOODERHAM, OF TORONTO, ONTARIO, CANADA.

APPARATUS FOR TREATING HYDROCARBONS.

Application filed October 28, 1921, Serial No. 511,042. Renewed January 8, 1923.

To all whom it may concern:

Be it known that I, STEPHEN LOUIS GARTLAN, a citizen of the United States of America, residing at the city of Toronto, in the 5 county of York and Province of Ontario, Dominion of Canada, have invented certain new and useful Improvements in Apparatus for Treating Hydrocarbons; and I hereby declare that the following is a full, clear, 10 and exact description of the same.

It is known that a natural telluric hydrocarbon is a mixture of substances of varying boiling points, and that each of the hydrocarbons of higher boiling points contained 15 in such mixtures is, during the process of distillation, exposed to various degrees of temperature below its own boiling point, so long as the hydrocarbons of lower boiling points are not removed from the still, and 20 that the separation of these hydrocarbons by distillation is often difficult for fractions boiling as low as 200° C., on account of the ease of partial decomposition of the higher boiling fractions at ordinary atmospheric 25 pressure.

It is also known in the cracking of heavy oils, that two essential factors govern, largely, the reactions that take place, namely temperature and pressure, the function of 30 increased temperature being to break the bonds of groups that make up the complex hydrocarbon molecule, and the function of pressure which is of chief importance, being to exert an influence on the nature of the 35 resulting product.

Broadly speaking, cracking operations have heretofore been divided into two principal types; those that involve cracking at atmospheric pressure and those that involve 40 cracking under increased pressure.

The disadvantage of operations involving cracking at atmospheric pressure is the formation of relatively large volumes of olefins and the tendency of the hydrocarbons to 45 pass out of the reacting sphere with a small degree of alteration; and the difficulty of obtaining cracking in any effective degree in operations operating without pressure, is that the higher temperatures cannot 50 be attained without causing vaporization and without pressure the vapors cannot be held in the heated zone. The degree of con-

version is necessarily less at atmospheric pressure than under high pressure, as on account of the greater stability of the lighter 55 molecules only the heavier molecules are subject to alteration.

Great danger is inherent in cracking operations in which a large volume of liquid is heated under pressure in a still or other 60 large container, as a liquid-vapor phase system necessitates the employment of a given pressure for given temperature and vice versa, unless one of the phases be caused to disappear. Therefore, in order to reach 65 the high temperatures that are desirable in order to reach the high temperatures that are desirable in order to bring about a maximum of cracking, it is necessary to use correspondingly high pressures if the two phase 70 system is to be maintained. This simultaneous use of both high temperatures and high pressures in the same vessel is a source of danger when a large volume of liquid is heated in a single operation, as the container 75 is apt to give way and the great volume of highly heated liquid then becomes a serious menace.

Operations of the above nature are also subject to the limitation common to all two 80 phase systems namely, that the temperature and pressure cannot be varied independently of each other. This fixed interdependence of temperature and pressure has heretofore been one of the greatest handicaps of 85 all two phase systems, for the higher temperatures and pressures, favorable for cracking the lighter and intermediate fractions, cannot be attained in large operations because of the difficulty of finding retainers 90 that will withstand the necessary strain.

By conducting the vaporization at approximately atmospheric pressure and continuously withdrawing the vapors from the vaporizing zone, a continuous evolution of 95 the vapors can be maintained at temperatures which will permit of the vapors passing from the vaporizing zone with but a minimum alteration of the original hydrocarbon molecules, and then, by bringing 100 these vapors to a favorable temperature, the cracking operation can be carried on in a separate apparatus with maximum efficiency under controllable conditions of tem-

perature, pressure, and subsequent release of pressure for the sudden expansion of the compressed vapors, and will insure substantially all of the evolved vapors being broken down into the desired product.

To this end the vaporizing and cracking operations, are divided into distinct but interdependent stages and the temperature and pressure employed during the vaporizing 10 stage are varied independently of the temperature and pressure employed during the cracking stage, and in a two phase system, necessitating the employment of pressure and temperature, the pressure may be 15 caused to entirely disappear during the vaporizing stage. As a consequence, a large volume of liquid may be heated and the maximum vaporization may be attained in a single operation without danger of the 20 container giving way, and without danger of the large volume of highly heated liquid becoming a serious menace. And further the temperature and pressure during the vaporizing stage can be so controlled that 25 the evolved vapors will pass from the vaporizing zone with but a minimum alteration of the bonds of groups that make up the original hydrocarbon molecules and the vaporization, under these conditions, may be con- 30 tinued until an excessively low pressure in the vaporizer indicates that the maximum vaporization has been attained. These vapors after passing from the vaporizing zone, can be brought to a temperature, favor- 35 able to their alteration during the second or cracking stage by increasing, and maintaining the temperature attained during the vaporization, either before or during the period when the cracking pressure is exerted 40 on them, and the pressure during the cracking stage may be varied to meet the requirements of the reaction and afterwards released for the sudden expansion of the compressed vapors. This regulation of the tem- 45 peratures and pressures employed during the vaporizing and cracking stages gives control to a large extent, of the nature of the resulting product and the percentage of the original hydrocarbon treated which can be con- 50 verted into the resulting product.

This invention therefore, relates to a cracking operation consisting of distinct but interdependent stages by which the vaporization of hydrocarbons, particularly telluric 55 hydrocarbons, and the alteration of the original hydrocarbon molecules to form resulting products of different specific gravity and boiling points to the hydrocarbon vaporized may be continuously carried on in safety and 60 with maximum efficiency, and it consists essentially of:—conducting the vaporization under favorable conditions of temperature at atmospheric, or plus or minus atmospheric pressure, the degree of variation in 65 either direction from zero being negligible

and the heat applied during the vaporizing period being so regulated as to maintain a continuous evolution of vapors without appreciably altering the bonds of groups that make up the original hydrocarbon molecules; withdrawing the evolved vapors from the vaporizing zone during the vaporizing period, increasing, and maintaining, the temperature of the vapors attained during the vaporization to a degree favorable to the 75 cracking stage of the operation; compressing the vapors under controllable conditions of temperature and pressure and releasing the pressure after compression for their sudden expansion and the alteration of the original 80 hydrocarbons into liquefied resulting products of different specific gravity and boiling points to the hydrocarbon treated.

The objects of the invention are:—to enable the vaporization to be carried on at 85 relatively low temperatures, and under such conditions of pressure as will facilitate the rapid evolution of the vapors with but slight alteration of the original hydrocarbon molecules; to effect the alteration of these molecules by a controllable regulation of temperature and pressure, followed by release of pressure and sudden expansion to form a resulting product of a different specific 90 gravity and boiling points to the hydro- 95 carbon treated; and to eliminate the element of danger resulting from high pressures within the vaporizing sphere and the element of failure of the apparatus resulting from high pressures during the vaporization. 100

In carrying out these objects a suitable vaporizing apparatus is employed in which a large volume of hydrocarbon matter can be exposed to heat. A steam generator may be connected with the vaporizing apparatus 105 for the injection of steam into the hydrocarbon or hydrocarbon vapors during the vaporizing period to increase the degree and rate of vaporization. A superheater may be connected with the vaporizing apparatus to 110 raise the temperature of the vapors to a degree favorable to the cracking stage of the operation. A compressor, suitably jacketed for heating and cooling purposes, is connected directly with the vaporizing appa- 115 ratus and with the superheater for, continuously withdrawing the evolved vapors from and maintaining a diminished pressure within the vaporizing zone and superheater and compressing the vapors under condi- 120 tions of heat exchange favorable to the requirements of the reaction, and an expansion chamber is connected with the compressor for releasing the pressure after compression for the sudden expansion of the 125 vapors.

In a series of tests conducted according to this invention kerosene fractions have been vaporized by boiling the mass at temperatures ranging from 160° C. to 300° C. 130

and heavy Mexican crude petroleum hydrocarbons have been vaporized by boiling the mass at temperatures ranging from 98° C. to 415° C. and the vapors have been altered 5 into other hydrocarbon fractions with a compressor operating at pressures up to 1500 pounds, and at temperatures up to 550° C. during the compression, the pressure after compression being released for the sudden 10 expansion of the vapors.

The drawing is a diagrammatic view of a suitable arrangement of apparatus by which the operation may be effectively carried out.

15 In the practical operation of the invention it has been found that the following method and apparatus produce satisfactory results both as regards yields of the desired hydrocarbon products and economy of operation, 20 but other apparatus of any usual or approved type may be substituted for that hereinafter described and the specific temperatures and pressures may be varied to the character or conditions of the hydrocarbons 25 treated.

The plant in which this process was elaborated consists of a 50 H. P. tubular type boiler 8 for steam generating purposes connected:—to an engine 16 which drives the 30 compressor 5; to the steam coil 3 of the superheater 2; and to the outer jacket of the compressor 5. The superheater 2 is an oil fire heated box of brick construction containing two sets of coils 3 and 4 for 35 superheating the steam from the boiler, and the vapor from the still or vaporizer.

40 The superheater is provided with a burner or burners 25 connected with a fuel supply by a pipe 26, and these burners are supplied with a steam jet from the steam pipe line 15.

The vaporizer 1 is of cylindrical construction of a total volume of approximately 100 gallons and is provided with temperature and pressure recording instruments. Connected with it is one of the steam lines from the superheater and two vapor lines, one of the vapor lines leading through the superheater to the compressor. The compressor, 45 provided with temperature and pressure recording instruments, is of the three stage type, having an outer jacket such as is commonly used for cooling purposes, and has a capacity of twelve cubic feet per minute, at 50 R. P. M. The compressor is connected 55 with the intake 18 of the expansion chamber 17, through a needle valve 19, and both compressor and expansion chamber are capable of withstanding high pressures. The expansion chamber 17 consists of a steel cylinder with a total volume of about 2½ cubic feet and is capable of withstanding high pressures up to approximately 2,000 pounds. The cooler 21 is of the usual spiral type 60 consisting of about thirty feet of one and one quarter inch coiled pipe and the receiv-

ing tank 23 is of thirty gallon capacity and capable of withstanding pressures up to 300 pounds.

The liquid hydrocarbons to be treated are introduced into the vaporizer 1 which is 70 provided with burners 12 connected by a pipe line 13 with the source of fuel supply and when oil is used as fuel the burners are also connected by a pipe line 15 with the steam coils 3 of the superheater 2, the steam 75 flowing through the pipe line 15 to the burners atomizing the oil and spraying it, under pressure, through the burner outlets. The vaporizer 1 takes the form of a cylindrical still, but it may take the form of an 80 apparatus of any other design which will provide for the continuous evolution of a relatively large volume of vapors and may be charged and run in batches or a number of them may be connected with one or more 85 compressors, and run simultaneously, or a number of them may be connected in series and run simultaneously, the oil circulating in the latter case from one to another of the series; or it may take the form of a tube 90 or set of tubes of similar vaporizing capacity, and in an apparatus of tubular construction, satisfactory results may be obtained by continuously injecting the oil into the tube or series of tubes suitably heated 95 to continuously evolve vapor.

In the construction shown in the drawings, the vaporizer is provided with two valve controlled vapor pipes 6 and 7 leading from the vaporizing zone, the valve controlled 100 pipe 6 directly connecting the vaporizer with the compressor at the usual intake port on the low pressure cylinder and conducting the vapors directly from the vaporizer to the compressor 5, and the valve controlled 105 pipe 7 conducting the vapors from the vaporizer to the coil 4 of the superheater 2, and then to the valve controlled pipe 6, between its valve 6' and the intake port of the compressor 5. To minimize the drop in 110 temperature between the vaporizer or superheater and the compressor, the pipes 6 and 7 may be suitably covered with heat insulating material. The steam coil 3 in the superheater 2 is connected with the steam 115 generator 8 and supplies superheated steam to the vaporizer through the steam pipe 10.

To facilitate the cracking of the vapors it is necessary to maintain the compressor at a temperature favorable to the maximum 120 cracking efficiency. In treating Texas fuel oil the compressor was preheated to a temperature up to 550° C. and this temperature was maintained for the compressor during the evolution of the vapors of those fractions evolved by boiling the mass at temperatures between 124° C. and 400° C. When the temperature of the mass for the evolution of the vapors of the higher boiling fractions exceeded 400° C., it was found 125 130

advisable to reduce the temperature of the compressor to about 450° C.

For the purpose of maintaining an effective operating temperature, the compressor is provided with a coil or jacket for heating and cooling purposes. The intake end of this coil or jacket is connected with the main steam pipe line 9 by a valve controlled steam pipe 11, and with the steam coil 3 in the superheater 2 by a valve controlled pipe 15.

Steam circulates from the steam boiler through the valve controlled pipe 15 and superheater, to the jacket of the compressor to externally preheat the compressor before the vapors are evolved in the vaporizer. In the treatment of the Texas fuel oil previously mentioned the compressor was maintained at a temperature of about 550° C. during the compression of the hydrocarbon fractions vaporizing at or below 400° C. When the boiling temperature of the mass attained 400° C., the steam from the superheater to the coil or jacket of the compressor was cut off, and when the boiling temperature of the mass exceeded 400° C., the steam circulated from the steam generator by means of the pipe lines 9 and 11, to the compressor and effected a heat exchange or reduction of temperature of the compressor to about 450° C., the temperature of the compressor at all times being controlled to the requirements of the cracking temperature of the vapors being compressed. When it is necessary to effect a considerable reduction in the temperature of the compressor, suitable mechanical cooling means may be connected with the compressor for that purpose.

Connected with the intake 18 of the expansion chamber 17 and the exit of the high pressure cylinder of the compressor is a vapor line 20, and this high pressure vapor line is covered with suitable insulating material to minimize the drop in temperature. The expansion chamber is provided with a gauge glass so that the apparent condition and the rate of collection of the liquefied vapors may be observed. When the oil is introduced into the vaporizer, steam pressure is raised in the steam generator to about 100 pounds and the burners in the superheater are lighted and so regulated as to superheat the steam from the generator and the vapor passing from the vaporizer through the superheater to the compressor to a temperature up to 550° C. Steam from the superheating coil 3 is then conducted through the coil or jacket of the compressor to preheat the compressor to approximately the same temperature. The burners in the vaporizer are now lighted and the temperature raised until vapors are evolved. The evolution of the vapors may be continued until an excessively low pres-

sure in the vaporizer indicates that the maximum vaporization of the oil introduced into the vaporizer has been attained. When the vapors begin to be evolved, the compressor is started and the vapors are withdrawn by the compressor from the vaporizer through the vapor coils 4 of the superheater. The temperature of the superheater is so regulated as to heat the vapors or the low boiling fractions, before compression, to a temperature of about 550° C. which is found to be favorable to the cracking stage of the operation.

When the vapors passing through the superheater pick up sufficient heat to keep the compressor at the proper operating temperature, the superheated steam to the coil or jacket of the compressor is turned off. When the temperature of the hydrocarbon in the vaporizer reaches the maximum boiling point before cracking, the vapors are conducted direct from the vaporizer to the compressor. When the temperature of the compressor exceeds 550° C. wet steam from the steam generator is turned into the coil or jacket through the pipes 9 and 11. The introduction of this wet steam into the coil or jacket of the compressor has the effect of reducing the temperature of the compressor, thereby preventing an abnormal rise in its temperature, due to the high temperature of the vapors of the higher boiling fractions and any heat developed by the compression.

Instead of using the superheater to preheat the vapors passing from the vaporizer to the compressor, the temperature of the compressor can be raised to a degree which will permit of the vapors passing direct from the vaporizing zone to the pressure zone at the vaporizing temperature and being heated by the compressor to the required degree for the cracking stage of the operation.

The temperature of the vaporizer is so regulated as to maintain a continuous evolution of the vapors and the speed of the compressor is so regulated as to continuously withdraw the vapors from the vaporizing zone and maintain in it a normal pressure at or about atmospheric pressure, the degree of variation from atmospheric pressure in either direction being negligible. The low pressure in the vaporizer facilitates the rapid evolution of the vapors; it enables the vaporization to be carried on at relatively low temperatures; it eliminates the risk of danger resulting from high pressures within the vaporizing sphere; and it eliminates the danger of failure of the apparatus resulting from high pressures.

The vaporization of the liquid is started at a relatively low temperature to vaporize the hydrocarbon fractions of low boiling point ranges, each fraction as it is vaporized

being drawn off from the vaporizer by the compressor, which action of the compressor maintains in the vaporizer a normal atmospheric pressure or pressure varying but little above or below atmospheric pressure.

When the vapors of the low boiling fractions have been evolved and withdrawn from the vaporizer, the temperatures of the vaporizer and its contents are increased to 10 continue the vaporization of the higher boiling fractions, the continuous withdrawal of these vapors being maintained by the compressor and the operation being continued until an excessively low pressure in the vaporizer indicates that the maximum vaporization has been attained.

When the vaporizing temperature reaches 200° C., superheated steam may be introduced into the vaporizer and the mixture of 20 vapors and steam is drawn off by the compressor through the superheater. The pressure in the high pressure cylinder is regulated to the requirements of the cracking operation and may vary from 100 pounds to 25 1,500 pounds or more per square inch. When the temperature of the mass for the evolution of the vapors reaches 400° C. the passage of the mixture of vapors and steam through the superheater may be discontinued and vapors may then be conducted directly to the compressor from the vaporizer.

The operation of the compressor is regulated to give any required pressure in the 35 high pressure cylinder. A practically constant flow of compressed vapors is maintained through the needle valve into the expansion chamber where the pressure is immediately reduced to or within a few pounds 40 of atmospheric pressure. During the compression the temperature of the vapors will approximate 550° C., and this temperature and the pressure are maintained until the delivery of the vapors through the needle 45 valve into the expansion chamber, where the vapors are suddenly expanded. The sudden expansion of the vapors causes a great drop in temperature and the liquefaction of all but the very lightest vapors. The strain 50 on the vapors caused by the high temperature and pressure in the compressor and the sudden expansion and great drop of pressure in the expansion chamber results in the alteration of the bonds of groups that 55 make up the original hydrocarbon molecules, and the formation of bonds of groups which make up hydrocarbon molecules of different specific gravity and boiling points or, in other words, this arrangement of heat 60 control, compression, and expansion, brings into use and renders possible the close control of the two well recognized factors made use of in the cracking of hydrocarbons, i. e., temperature and pressure, and brings into 65 operation an additional factor, i. e., the prin-

ciple of subjecting the hydrocarbon molecules to great strain by expansion.

For the condensation of those vapors not liquefied in the expansion chamber, the intake end of the cooler 21 is connected with 70 the outlet 22 of the expansion chamber 17 and this cooler 21 discharges into the receiver 23 where all liquefied vapors are collected, the differential pressure between the expansion chamber and receiving tank permitting of the unimpeded circulation of the liquefied products to the latter. In this way 75 everything except some of the permanent gases is collected in the receiving tank in the form of liquid of different boiling points 80 and specific gravity to those of the original hydrocarbon treated.

It has been ascertained in the practical operation of this method of treating hydrocarbon oils such as heavy paraffin base or 85 asphaltum base crude oils, containing practically no natural naphtha, that yields as high as 31% of gasoline have been obtained on a single run on the batch system.

It will be understood that the above mentioned temperatures and pressures have been merely set forth as one specific example of the practical application of the process and that they may be varied to meet the requirements of the operating conditions of a commercial plant.

Having thus fully described my invention, what I claim as new and desire to secure by Letters Patent is;—

1. The herein-described cracking apparatus 100 for the production of lower boiling hydrocarbons comprising means for vaporizing the hydrocarbon mass at about atmospheric pressure, means for continuously withdrawing the vapors from the vaporizing zone 105 during the vaporizing period and compressing all of them under regulable conditions of pressure, and means for releasing the pressure after compression for the sudden expansion and liquefaction of the vapors to 110 form a resulting product differing in specific gravity and boiling points from the hydrocarbon vaporized.

2. The herein-described cracking apparatus 115 for the production of lower boiling hydrocarbons comprising means for vaporizing the hydrocarbon mass at about atmospheric pressure, means for continuously withdrawing the vapors from the vaporizing zone during the vaporizing period and compressing all of them under regulable conditions of temperature, and means for releasing the pressure after compression for the sudden expansion and liquefaction of the vapors to 120 form a resulting product differing in specific gravity and boiling points from the hydrocarbon vaporized.

3. The herein-described cracking apparatus 125 for the production of lower boiling hydrocarbons comprising means for vaporizing 130

the hydrocarbon mass at about atmospheric pressure, means for continuously withdrawing the vapors from the vaporizing zone during the vaporizing period and compressing all of them under regulable conditions of temperature and pressure, and means for releasing the pressure after compression for the sudden expansion and liquefaction of the vapors to form a resulting product differing 10 in specific gravity and boiling points from the hydrocarbon vaporized.

4. The herein-described cracking apparatus for the production of lower boiling hydrocarbons comprising means for vaporizing the hydrocarbon mass at about atmospheric pressure, means for withdrawing the vapors from and maintaining a pressure of about one atmosphere in the vaporizing zone continuously during the vaporizing period and 20 then compressing all of the vapors, means for releasing the pressure after compression for the sudden expansion and liquefaction of the vapors to form a resulting product differing in specific gravity and boiling points 25 from the hydrocarbon vaporized, and means for regulating the temperature of the evolved vapors on passing from the vaporizing zone to a degree favorable to the compression and subsequent expansion.

5. The herein-described cracking apparatus for the production of lower boiling hydrocarbons comprising means for vaporizing the hydrocarbon mass at about atmospheric pressure, means for compressing all the 35 evolved vapors, means for expanding them after compression and means for regulating the temperature of the vapors on passing from the vaporizing zone to a degree favorable to the alteration of the bonds of groups 40 that make up the original hydrocarbon molecules to form a resulting product differing in specific gravity and boiling points from the hydrocarbon vaporized.

6. The herein-described cracking apparatus 45 for the production of lower boiling hydrocarbons comprising means for vaporizing the hydrocarbon mass, means for withdrawing the vapors from the vaporizing zone and continuously maintaining in it a pressure of 50 about one atmosphere and compressing all the vapors on passing from the vaporizing zone, and means for releasing the pressure after compression for the sudden expansion and liquefaction of the vapors.

7. The herein-described cracking apparatus 55 for the production of lower boiling hydrocarbons comprising means for vaporizing the hydrocarbon mass at about atmospheric pressure, means for increasing and maintaining the temperature of the evolved vapors on passing from the vaporizing zone to a degree favorable to the cracking operation, 60 means for withdrawing the vapors from the vaporizing zone and compressing all of 65 them, and means for releasing the pressure

after compression for their sudden expansion and liquefaction to form a resulting product of different specific gravity and boiling points to the hydrocarbon vaporized.

8. The herein-described cracking apparatus 70 for the production of lower boiling hydrocarbons comprising means for vaporizing the hydrocarbon mass at about atmospheric pressure, means independent of the vaporizing means for regulating the temperature of the evolved vapors to a degree favorable to the cracking operation, means for withdrawing the vapors from the vaporizing zone and compressing all of them, and means for releasing the pressure for the sudden expansion of the vapors after compression. 75

9. The herein-described cracking apparatus for the production of lower boiling hydrocarbons comprising means for vaporizing the hydrocarbon mass at about atmospheric pressure, means for regulating the temperature of the vapors, after passing 80 from the vaporizing zone, to the requirements of the cracking reaction, means for withdrawing the vapors from the vaporizing zone and compressing all of them, and means for releasing the pressure after compression for the sudden expansion and liquefaction 85 of the vapors. 95

10. The herein-described cracking apparatus for the production of lower boiling hydrocarbons comprising means for vaporizing the hydrocarbon mass at about atmospheric pressure, a superheater for raising the 100 temperature of the vapors after passing from the vaporizing zone to the requirements of the reaction, means for compressing all of the vapors, and means for releasing the pressure after compression for the 105 sudden expansion and liquefaction of the vapors.

11. The herein-described cracking apparatus for the production of lower boiling hydrocarbons comprising means for vaporizing the hydrocarbon mass, means for superheating the vapors of the low boiling fractions after passing from the vaporizing zone, a compressor for withdrawing the vapors from the vaporizing zone and maintaining in it a pressure of about one atmosphere and compressing all of the vapors, means 110 regulating the temperature of the compressor to a degree favorable to the reaction, and means for releasing the pressure after compression for the sudden expansion and liquefaction of the vapors. 115

12. The herein-described cracking apparatus for the production of lower boiling hydrocarbons comprising means for vaporizing the hydrocarbon mass at about atmospheric pressure, a superheater for increasing the temperature of the vapors of the low boiling fractions on passing from the vaporizing zone, a compressor for withdrawing 120 130

- the vapors from the vaporizing zone and compressing all of them, means for regulating the temperature of the compressor to a degree favorable to the reaction, and means 5 for releasing the pressure after compression for the sudden expansion and liquefaction of the vapors.
13. A cracking apparatus for the production of lower boiling liquid hydrocarbons 10 comprising means for vaporizing liquid hydrocarbon, means for transferring all the evolved vapors from the vaporizing zone to a separate pressure zone and means for compressing them in said separate pressure 15 zone, and means for heating the transferred vapors at will, to a degree favorable to the alteration, during the transference of said vapors from the vaporizing zone to the pressure zone.
14. A cracking apparatus for the production of lower boiling liquid hydrocarbons comprising means for vaporizing liquid hydrocarbon, means for transferring all the evolved vapors from the vaporizing zone to 20 a separate pressure zone and means for compressing them in said separate pressure zone, and means for heating the transferred vapors at will before the compression to a degree favorable to the alteration.
15. A cracking apparatus for the production of lower boiling liquid hydrocarbons comprising means for vaporizing liquid hydrocarbon, means for transferring all the evolved vapors from the vaporizing zone to 25 a separate pressure zone and means for compressing them in said separate pressure zone, and means for heating the transferred vapors at will before the compression to a degree favorable to the alteration.
16. A cracking apparatus for the production of lower boiling liquid hydrocarbons comprising means for vaporizing liquid hydrocarbon, means for transferring all the evolved vapors from the vaporizing zone to 30 a separate pressure zone and means for compressing them in said separate pressure zone, and means on the transfer line between the vaporizing zone and pressure zone for heating the transferred vapors at will to a degree favorable to the alteration.
17. A cracking apparatus for the production of lower boiling liquid hydrocarbons comprising means for vaporizing liquid hydrocarbon, heated means for transferring all the evolved vapors from the vaporizing zone 35 to a separate pressure zone and means for compressing all the transferred vapors in said separate pressure zone under controllable conditions of pressure and means for releasing the compression for the sudden expansion of the compressed vapors.
18. A cracking apparatus for the production of lower boiling liquid hydrocarbons comprising means for vaporizing liquid hydrocarbon, heated means for transferring all 40 the evolved vapors from the vaporizing zone to a separate pressure zone and means for compressing all the transferred vapors in said separate pressure zone under controllable conditions of temperature and means for releasing the compression for the sudden expansion of the compressed vapors.
19. A cracking apparatus for the production of lower boiling liquid hydrocarbons comprising means for vaporizing liquid hydrocarbon, heated means for transferring all the vapors from the vaporizing zone to a separate pressure zone and means for compressing all the transferred vapors in said 45 separate pressure zone under controllable conditions of temperature and pressure and means for releasing the compression for the sudden expansion of the compressed vapors.
20. A cracking apparatus for the production of lower boiling liquid hydrocarbons comprising means for vaporizing liquid hydrocarbon, means for transferring all the vapors to a separate pressure zone and compressing all the transferred vapors in said 50 separate pressure zone, means for releasing the pressure after compression for the sudden expansion of the vapors, and means for regulating the temperature of the transferred vapors at will, to the requirements of the reaction, during the transference of said vapors from the vaporizing zone to the pressure zone.

Washington, D. C., October 26th, 1921.

STEPHEN LOUIS GARTLAN.
